UNITED STATES PATENT OFFICE.

GEORGE E. CONWAY, OF TENAFLY, NEW JERSEY.

INTERNAL-COMBUSTION ENGINE.

1,366,636.

Specification of Letters Patent. Patented Jan. 25, 1921.

Application filed May 3, 1919. Serial No. 294,373.

To all whom it may concern:

Be it known that I, GEORGE E. CONWAY, a citizen of the United States, residing at Tenafly, in the county of Bergen and State 5 of New Jersey, have invented a certain new and useful Improvement in Internal-Combustion Engines, of which the following is a specification.

The invention relates to motors for airplane and like service in which economy of space and weight are important factors, and the object of the invention is to provide an engine in which the disposition of the cylinders, preferably tandem, permits the engine 10 to be very compact and to occupy but little space in cross-section; and disposing the pistons in such cylinders so that the power impulses are applied on opposite sides of the crank-shaft, thereby balancing the effect 15 of the impulses and eliminating vibration.

A further object is, by the arrangement of cylinders and pistons, to obtain the advantages of long compression strokes with a reduced piston-speed, and to obtain an increase 20 in explosions without exceeding the limit of maximum piston-speed, thus increasing the efficiency or horsepower output.

Another general object is to provide an engine in which the valve-operating, and 25 lubricating means are simple and positive, and which is entirely self-contained, easily constructed and economically maintained.

The invention consists in certain novel 30 features of construction and arrangement by which the above objects are attained, to be hereinafter described and claimed.

The accompanying drawings form a part 35 of this specification and show the invention as applied to an engine having two groups 40 or series of four cylinders each, designed for airplane service.

Figure 1 is a plan view of the engine with a portion of the casing removed, and partly in horizontal section.

Fig. 2 is a side elevation partly in vertical section.

Fig. 3 is a vertical section, partly in elevation, on a larger scale, showing the valve-operating mechanism.

Fig. 4 is a similar view showing one of the double pistons and the lubricating means therefor.

Fig. 5 is a transverse section through the casing and cylinder, showing the arrangement of piston-bars through which motion 55 is transmitted to the crank-shafts.

Fig. 6 is a perspective view showing the arrangement of the cranks diagrammatically.

Similar letters of reference indicate the 60 same parts in all the figures.

In the invention as shown in the drawings the cylinders are disposed horizontally in two series, side by side in the same plane, four cylinders in each series, mounted in 65 the bed portion of a casing which with its cover incloses the engine and also serves as the frame for the latter. The cylinders of each series are in axial alinement or tandem to each other.

The arrangement on each side of the center line of the casing is a counterpart of the other and the cylinders of only one series are shown, see Fig. 1, in which they are marked from front to rear, A, A¹, A² and 75 A³. The cylinders are firmly held in the bed M or lower half of the casing and are fully inclosed when the cover M¹ of the casing is applied and secured along the horizontal joint between them. Each cylinder 80 is open at the ends and separated from the next, and contains two pistons arranged to move oppositely, the space between the piston-heads serving as a combustion chamber in which the mixture of hydrocarbon and 85 air is received, compressed and exploded, and from which the exhaust or spent gases are expelled and led away. The force of the explosion is exerted to separate the piston-heads.

The extreme end pistons B and B⁷ are single and reciprocate in the outer ends of the cylinders A and A³; the intermediate pistons are double, or in pairs fixedly joined together, one in each adjacent cylinder. 95 The double pistons B¹ B² are received in the adjacent ends of cylinders A, A¹, the pistons B³ B⁴ in the cylinders A¹, A², and the pistons B⁵, B⁶ in cylinders A², A³.

Sufficient space is provided between the 100 adjacent ends of the intermediate cylinders and beyond the ends of the outer cylinders A, A³ to permit arms connected to the pistons to extend radially and oppositely outward beyond the cylinders and reciprocate freely in spaces m provided therefor in the casing M, M¹, transmitting the movements of the pistons to four piston-bars arranged parallel with the cylinders and adapted to act on a crank-shaft. Two of the bars D and D¹ lie in a plane horizontally with the 105 axial line of the cylinders, and the other

pair $D^2 D^3$ lie in a vertical plane at a right angle to the other.

The arms C of the double pistons $B^1 B^2$ and $B^5 B^6$ are secured to the horizontally arranged bars D and D^1 , and the arms C^1 of the single pistons B and B^7 and arms C^2 of the double piston $B^3 B^4$ are secured to the vertically arranged piston-bars $D^2 D^3$. Obviously all the pistons thus connected reciprocate together as a unitary whole and in coaction with the others condition the cylinders for intake, compression, explosion, and exhaust in the prescribed order.

At the forward ends the bars D and D^1 are forked to receive connecting rods $E E^1$ on cranks $F^1 F^4$ of the crank-shaft F , arranged oppositely but in the same plane with each other, and on trunnions at the sides of the arms C^1 at the front, are connecting rods $E^2 E^3$ from the piston-bars $D^2 D^3$, to the intermediate cranks $F^2 F^3$ on the crank-shaft F , in the same plane as the cranks $F^1 F^4$ but extending oppositely thereto. The crank-shaft F lies transversely of the casing and is mounted in bearings M^2 therein.

The companion series of cylinders and pistons is similarly equipped and arranged to act on the cranks $G^1 G^2 G^3$ and G^4 of a crank-shaft G , in line with the shaft F , but with its cranks set at a right angle to those on the latter, see Fig. 6.

On each crank-shaft, shown as between the cranks $F^2 F^3$ and $G^2 G^3$, is a beveled gear-wheel H^2 in mesh with a beveled gearwheel H^1 on a short propeller shaft H extending forwardly parallel with the cylinders and mounted in bearings in the casing M , M^1 , one of which is the outboard antifriction 40 thrust bearing M^3 .

On the inner end of the propeller shaft is a pinion H^3 in mesh with a gearwheel I^1 on a drive-shaft I mounted in bearings in the cover M^1 and centrally between and 45 parallel with the two series of cylinders. The drive-shaft carries pinions I^2 in mesh with a corresponding series of gearwheels J mounted on studs set in the chambers M^4 of the casing. Each wheel J carries a cam 50 J^1 on one face and a similar cam J^2 on the opposite face set at a right angle to the first. The cams operate the valves controlling the inlet and exhaust passages from the ports a of the cylinders.

55 The valves are of the mushroom type mounted in the casing-cover M^1 with their stems horizontal and parallel with the cylinders and drive-shaft I and in alinement with each other. Each wheel J operates 60 two oppositely disposed valves controlling either inlet or exhaust passages.

The stem K^1 of each valve K has a sleeve K^2 screwed thereon provided with a nose K^3 adapted to be acted upon by the cam and 65 move the valve axially from its seat and

admit the explosive mixture to the cylinder, or permit the spent gases to escape therefrom. The screw-threaded end of the valve-stem is slotted as at k , see Fig. 3, to receive a pin k^1 extending diametrically through the sleeve and stem to hold these parts against relative movement after adjustment for length has been made. The other end of the sleeve has a rounded lug K^3 on each side of the stem, received each in a corresponding notch l in the fork L^1 of the bifurcated arm of a bell-crank lever L fulcrumed at l^1 on the casing below the valve stem and having a short arm L^2 carrying a rod L^3 extending downwardly through the casing. The rod L^3 carries a head L^4 forming an abutment for the lower end of an expansion spring L^5 abutting at the upper end against the casing, and exerting its force through the lever L to hold the valve yielding to its seat.

The electrical distribution to the several spark-plugs P of the ignition system, is effected through mechanism, not shown, which may be as usual, located in a portion M^6 of the casing, see Fig. 2, and actuated from a beveled gearwheel I^3 on the drive-shaft I .

From a carburetor, not shown, the explosive mixture is received through a vertical conduit N having lateral branches $N^1 N^1$ leading to passages $N^2 N^2$ in the cover M^1 , controlled by the inlet valves, through which it is delivered to the valve-chamber m^2 , and thence through the cylinder ports a to the combustion chamber between adjacent piston-heads. The exhaust escapes through the same ports to the valve-chambers and past the exhaust valves to the passages N^3 N^3 which are all connected by a manifold, 100 not shown, and led away as usual.

As before stated the casing is in two portions M and M^1 joined together, and is cored to provide water-jackets M^4 through which the cooling liquid is circulated by any 110 suitable pump, not shown, operated from the drive-shaft I . The casing also serves as the frame for the engine and completely encloses the latter.

Lubricating oil is forced by a pump, indicated at M^5 , through pipes R to spaces in the covers communicating with the interior of the tubular piston-bars; in Fig. 4 m^1 is a space in the sleeve M^6 inclosing the upper piston-bar D of the vertical pair of bars D , D^1 . Oil enters the bar through the perforations d and escapes through the perforation d^1 to the recess c in the arm C of the piston, whence it is led by branch pipes $R^1 R^1$ to the annular groove b in each piston-head and thus lubricates the cylinders and pistons. The end pistons B , B^7 and the pistons connected by the horizontally arranged bars $D^2 D^3$ are similarly supplied.

Each of the two groups or series of cylin- 130

- ders and pistons, acts as a four cylinder four cycle engine, and the two series work independently through beveled gearing on the shafts F and G, on the propeller-shaft H.
- 5 The cycle of intake, compression, explosion and exhaust for each cylinder is so timed in relation to the disposition of the cranks on the crank-shafts F and G as to deliver two power impulses in each revolution of each 10 shaft, and as the cranks of each shaft are set at an angle of 90° to those of the other, the result is the delivery of four power impulses in each complete revolution of the two crank-shafts, transmitted to the propeller-shaft.
- 15 By arranging the cylinders in tandem in a horizontal plane, the desired compactness is attained and the engines occupy but little lateral space or cross-sectional area.
- 20 By employing two pistons in each cylinder with a combustion chamber between and formed by the piston-heads, and by connecting together all the pistons moving in the same direction, and connecting together all 25 the pistons moving in the opposite direction, the power impulses are applied to the crank-shafts on diametrically opposite sides, which results in balancing such impulses and eliminating vibration.
- 30 The combined short strokes of the two pistons in each cylinder affords all the advantages of a long compression stroke, with a reduced piston speed, thus permitting a greater number of explosions to take place 35 within the maximum piston speed limit for internal combustion engines, which results in an increased horsepower output in this type of engine over that attainable in the usual type having the same number of cylinders and piston displacement. The advantage gained is lighter metal weight per 40 horsepower developed.
- 45 Although the improved motor is especially adapted for airplane service and is designed for such work, it will be understood that the invention may be applied to engines designed for any service to which it may be adapted; and modifications may be made in the forms and proportions and in various 50 details of construction without departing from the principle of the invention or sacrificing its advantages.
- 55 The number of cylinders in the two series may be varied, or a single series alone may be employed.
- 60 I claim:
1. In an internal combustion engine, four cylinders arranged in axial alinement, two pistons in each cylinder, a crank shaft common to all of said pistons, the space between such pistons forming a combustion chamber, means connecting together the group of pistons moving in one direction, and means connecting together the group 65 of pistons moving in the opposite direction, and means for delivering a plurality of power impulses at each revolution of said shaft.
2. In an internal combustion engine, four cylinders arranged in axial alinement and separated from each other, a crank shaft common to all of said pistons, two pistons in each cylinder, the space between such pistons forming a combustion chamber, arms on said pistons extended outwardly in the space between said cylinders, means connecting together the arms of the group of pistons moving in one direction, means for connecting together the arms of the group of pistons moving in the opposite direction, and means for delivering a plurality of power impulses at each revolution of said shaft.
3. In an internal combustion engine, four separated cylinders arranged in axial alinement, two pistons in each cylinder, the space between such pistons forming a combustion chamber, arms on said pistons extended outwardly in the spaces between said cylinders, the arms of the group of pistons moving in one direction arranged to lie in a horizontal plane, and the arms of the other group of pistons moving in the opposite direction arranged to lie in a vertical plane, bars connecting such horizontally disposed arms, and bars connecting such vertically disposed arms, a crank-shaft common to all of said pistons, and connecting-rods from said bars to oppositely disposed cranks on said shaft, the cycles of intake, compression, explosion, and exhaust for such series of four cylinders being timed to give two effective impulses at each revolution of the crank-shaft.
4. In an internal combustion engine, a plurality of separated cylinders arranged in axial alinement, two oppositely moving pistons in each cylinder, a crank shaft common to all of said pistons, the space between such pistons forming a combustion chamber, connections extending across the space between adjacent cylinders and joining together the adjacent pistons of both, arms on said connections extended outwardly in the spaces between said cylinders, means connecting together the arms of the group of pistons moving in one direction, means connecting together the arms of the group of pistons moving in the opposite direction, and means for delivering two effective power impulses of both groups of pistons to the said crank-shaft at each revolution of said shaft.
5. In an internal combustion engine, a plurality of separated cylinders arranged in axial alinement, two pistons in each cylinder, the space between such pistons forming a combustion chamber, arms on said pistons extended outwardly in the spaces between said cylinders, tubular bars connecting said arms, and means for supplying lubricating oil through said bars to said pistons and cylinders.

6. In an internal combustion engine, four separated cylinders arranged in axial alinement, pairs of oppositely moving pistons in said cylinders, connected to a common crank shaft to give two effective impulses at each revolution of said shaft, the space between such pistons forming a combustion chamber, valves controlling admission and exhaust passages for such combustion chambers, a drive-shaft disposed parallel with said cylinders and means for rotating it, and means actuated by said drive-shaft for operating said valves.
7. In an engine of the character set forth, a casing, four cylinders arranged in axial alinement therein and having cylinder ports, and pistons in said cylinders connected to a common crank shaft to give two effective impulses at each revolution of said shaft, valve chambers in said casing and passages leading to said ports, a drive-shaft arranged parallel with said cylinders, wheels in said casing having cams thereon and driven by said drive-shaft, and valves controlling said passages and operated by said cams.
8. In an internal combustion engine, four cylinders arranged in axial alinement in a series, four cylinders arranged in axial alinement in a second series in the same plane with the first, pairs of pistons in said cylinders connected to a common crank shaft to give two effective impulses at each revolution of said shaft, the space between such pistons forming a combustion chamber, a crank-shaft for each series, valves controlling the ports of such combustion chambers, a drive-shaft extending between said two series and parallel therewith, and means actuated by said drive-shaft for operating the valves of both series.
9. In an internal combustion engine, four cylinders arranged in axial alinement in a series, four cylinders arranged in axial alinement in a second series in the same plane with the first, pairs of pistons in said cylinders connected to a common crank shaft to give two effective impulses at each revolution of said shaft, the space between such pistons forming a combustion chamber, a crank-shaft for each series, and a propeller shaft driven by both said crank-shafts, valves controlling the ports of such
- combustion chambers, a drive-shaft extending between said two series and parallel therewith, means actuated by said drive-shaft for operating the valves of both series, and means for rotating said drive-shaft from said propeller shaft.
10. In an internal combustion engine, four cylinders arranged in axial alinement in a series, four cylinders arranged in axial alinement in a second series in the same plane as the first, pairs of pistons in said cylinders connected to a common crank shaft to give two effective impulses at each revolution of said shaft, the space between such pistons forming a combustion chamber, a crank-shaft for each series, a beveled gear-wheel on each of said crank-shafts, a propeller shaft, and a beveled gearwheel on said propeller shaft in mesh with both of said beveled gearwheels on said crank-shafts, and a drive-shaft rotated from said propeller shaft and arranged to operate said valves.
11. In an engine of the character set forth, a plurality of cylinders arranged in a casing in axial alinement and each having a port, a valve-chamber for each cylinder, passages from said chamber to said port, valves controlling said passages for two adjacent cylinders, a drive-shaft parallel with said cylinders, a pinion on said shaft, a gearwheel in said casing in mesh with said pinion, cams on the faces of said gearwheel, valve-stems on said valves arranged to be acted upon by said cams to open said passages, and spring actuated means for seating said valves.
12. In an engine of the character set forth, a plurality of cylinders, a double piston having two piston-heads and a connecting frame, an arm on said frame extending outwardly between adjacent cylinders each receiving one of said heads, a recess in said arm, a tubular bar joined to said arm and communicating with said recess, an annular channel in each of said heads, pipes leading from said recess to said channels, and means for supplying oil to the interior of said tubular bar.

In testimony that I claim the invention above set forth I affix my signature.

GEORGE E. CONWAY.
